PLATE GLASS SURFACING TABLE

William Owen, Pittsburgh, Pa., assignor to Pittsburgh Plate Glass Company, Allegheny County, Pa., a corporation of Pennsylvania

Application March 29, 1938, Serial No. 193,673

3 Claims. (CL 51—240)

The invention relates to tables for use in surfacing plate glass, in which the tables are passed in a continuous train beneath a series of grinding and polishing runners. The heat developed in the polishing operation causes the tops of the tables to warp or bow slightly, so that they are no longer true and flat, and when returned to the grinding end of the cycle for reuse, this bowed or warped condition persists to a certain extent, so that the glass sheets are not ground to uniform thickness, the sheets being ground thinner in the portions overlying the centers of the tables than those overlying the sides of the tables. The object of the present invention is to provide an improved table construction in which the warping of the table tops due to the heat developed in polishing is substantially eliminated. A further object is the provision of a surfacing table having the characteristics specified which is no more costly than the standard surfacing table and which has the same rigidity and durability. One embodiment of the apparatus is shown in the accompanying drawings, wherein:

Figure 1 is a plan view. Fig. 2 is a side elevation. Fig. 3 is a transverse section on the line III—III of Fig. 1. And Fig. 4 is an enlarged partial section also on the line III—III of Fig. 1.

Referring to the drawings, 5 is the body portion of the table preferably of cast steel or cast iron carried upon the wheels 6, which ride upon the track 1. The upper portion of the car comprises the top 8 in the form of a plate of substantial thickness and the ribs 9 and 10 integral with the top. The ribs 9 extend transversely of the top while the ribs 10 extend longitudinally thereof, thus dividing the lower side of the top into rectangular sections, the ribs intersecting where they pass each other. This provides a very rigid construction, well adapted to stand the stresses incident to grinding and polishing. Along the edges of the plate 8 the usual pins 11 are provided extending through suitable perforations and serving as means for positively anchoring the glass sheet which is carried on the top of the table from lateral movement.

The upper surface of the top 8 is flat and smooth, and is provided with two sets of slots 12 and 13, the slots 12 extending the length of the table, while the slots 13 extend transversely thereof, thus dividing the top into a plurality of rectangular sections, as indicated in Fig. 1. These slots are formed by a sawing action, and as indicated in Fig. 3, extend down to a point below the level of the underside of the plate 8. They are preferably located on the center lines of the

ribs 9 and 10, which location permits the slots to be relatively deep without any appreciable weakening of the table top. This expedient of slotting the top of the table, substantially reduces any tendency to warping which would otherwise occur when the top is heated up due to the polishing action. When the top is sub-divided in this manner, each section 14 is independent of adjacent sections, so that while each section may warp slightly, the effect is not cumulative and the top as a whole remains substantially flat and true, even though raised to a relatively high temperature during the polishing operation. The upper portion of the grooves is preferably filled with plastic material 15, such as rubber for preventing the plaster used in cementing the glass to the table top from filling the grooves. As indicated above, the placing of the slots in alignment with the ribs permits these slots to be made relatively deep without adversely affecting the strength and rigidity of the table and constitutes a very deep, simple expedient for overcoming the difficulty as to warping heretofore referred to.

I am aware that it is not broadly new to saw a table top, so as to divide it into rectangular sections, as shown for example in the patent to Jacob Soderberg No. 1,983,009, dated December 4, 1934, but in such cases, the top is materially weakened intermediate the reinforcing ribs used on the underside of the top, and the car construction is made more complicated and expensive, as compared with the construction herein disclosed, wherein the slots are in line with the reinforcing ribs, so that there is no decrease in the rigidity of the table top, and it is possible to use one integral casting of about the same cost as a standard table.

What I claim is:

1. A plate glass surfacing table comprising a metal top plate having a flat upper face and a plurality of intersecting spaced longitudinal and transverse ribs projecting from the lower side of the plate and integral therewith, the upper side of the plate being provided with a plurality of intersecting longitudinal and transverse slots in line with said ribs dividing the upper face of the table into rectangular sections.

2. A plate glass surfacing table comprising a metal top plate having a flat upper face and a plurality of intersecting spaced longitudinal and transverse ribs projecting from the lower side of the plate and integral therewith, the upper side of the plate being provided with a plurality of intersecting longitudinal and transverse slots in line with said ribs dividing the upper face of the table into rectangular sections.

table into rectangular sections, said slots extending down into the ribs.

3. A plate glass surfacing table comprising a metal top plate having a flat upper face and a plurality of intersecting spaced longitudinal and transverse ribs projecting from the lower side of the plate and integral therewith, the upper side

of the plate being provided with a plurality of intersecting longitudinal and transverse slots in line with said ribs dividing the upper face of the table into rectangular sections, and a plastic filler in said slots.

WILLIAM OWEN.
